DESIGN FOR A GARMENT HANGER

Charles Gordon Xiques, Port Richmond, N. Y.

Application February 17, 1940, Serial No. 90,335

Term of patent 14 years

To all whom it may concern:

Be it known that I, Charles Gordon Xiques, a citizen of the United States of America, residing at Port Richmond, in the county of Richmond and State of New York, have invented a new, original, and ornamental Design for a Garment Hanger, of which the following is a specification, reference being had to the accompanying drawing, forming part thereof, and in which the figure is a perspective view of a garment hanger embodying my new design.

The characterizing features of the design re-

side in the garment hanger of the configuration shown consisting of a single wire strand bent to produce three parallel strakes disposed in a level plane, the side strakes being turned outwardly at their ends and the central strake being bent upwardly to form a hook, there being a central open space at the juncture of the hook elements, as shown.

I claim:

The ornamental design for a garment hanger, substantially as shown and described.

CHARLES GORDON XIQUES.
